(57) CLAIM

I claim the ornamental design for a backpack, as shown and described.

DESCRIPTION

FIG. 1 is a front view of a backpack showing my new design;
 FIG. 2 is a perspective view thereof;
 FIG. 3 is a rear view thereof;
 FIG. 4 is a rear perspective view thereof;
 FIG. 5 is a right side elevational view thereof;
 FIG. 6 is a bottom plan view thereof;
 FIG. 7 is a top plan view thereof;
 FIG. 8 is a right perspective view in an open position;
 FIG. 9 is an exploded front perspective view of the shell and pack;
 FIG. 10 is an exploded side perspective view of the shell and pack;
 FIG. 11 is a front perspective view of the pack portion; the shell being separated; and,
 FIG. 12 is an inside perspective view of the shell portion, separated from the pack.
